UNITED STATES PATENT OFFICE.

HENRY G. DAWSON AND WILLIAM R. DAWSON, OF CHICAGO, ILLINOIS.

DESIGN FOR A FIREPLACE.

SPECIFICATION forming part of Design No. 23,909, dated December 25, 1894.

Application filed November 26, 1894. Serial No. 530,070. Term of patent 7 years.

To all whom it may concern:

Be it known that we, HENRY G. DAWSON and WILLIAM R. DAWSON, citizens of the United States, residing at Chicago, in the county of Cook and State of Illinois, have invented and produced a new and useful Design for Fireplaces, of which the following is a specification reference being had to the accompanying photograph, showing the complete design.

10 The principal features of our design are the treatment of the vertical portion of the frame in representation of fluted square columns having composite capitals; the transverse portion of the frame representing an ornamental cornice uniting the columns and divided into panels by bands corresponding with the fluting of the shafts of the columns; the hood, shield and fender being ornamented with garlands; the upper part of the base 15 with sprays of leaves separated by bands of beading and the lower part thereof with festooned bands looped with tassels, all of this ornamentation being in relief.

The fluted columns are indicated at A, A, 20 the pedestals a, a, each having a single panel with floral adornment. The capitals of the columns each comprises a square panel b, b, with leaf adornment and a superstructure with convolute scrolls c, c, being modified 25 forms of the capitals of Ionic columns. At each end of the cornice D, is a rosette d, d, and the panels d', d', are each ornamented with bows of ribbon, with streamers supporting a garland, these panels being separated 30 by plain surfaces vertically fluted.

35 The hood E, has a central knot of ribbon e, with streamers and at each end a similar but smaller knot e', e'. Garlands of flowers e², e², unite the central knot with each of the end 40 knots and are looped also between the stream-

ers of the central knot. An inner hood E, is ornamented with a series of bands in scallop form. The ribbon and garland form of ornamentation is repeated in modified form on the shield F, the knots f, being in pairs with 45 a garland uniting the members of each pair and having pendent ends. The lower edge of the shield is furnished with a series of convolute scrolls.

A garland G, hangs from the two upper corners of the fender g, and has pendent ends. The base of the fender is ornamented with pendent fern leaves.

The base H, of the fire place has across its upper portion a belt ornamented with sprays 55 of leaves, h, inclined upwardly and away from the center and separated by lines of beading h'. The lower portion of the base H, represents three belts of festooned drapery h², with pendent tassels h³, at the junction of the festoon.

The cornice D, is surmounted by an egg and dart molding and the field of the hood E, and of the shield F, is chased or matted.

We claim as our invention—

65

The design for a fire place substantially as herein shown and described.

In witness whereof we have hereunto affixed our signatures in the presence of two witnesses.

HENRY G. DAWSON.

WILLIAM R. DAWSON.
